UNITED STATES PATENT OFFICE.

ESBON B. HATCH, OF AGEE, NEBRASKA.

FLOOR-CLAMP.

No. 806,342.

Specification of Letters Patent.

Patented Dec. 5, 1905.

Application filed June 9, 1905. Serial No. 264,502.

To all whom it may concern:

Be it known that I, ESBON B. HATCH, a citizen of the United States, residing at Agée, in the county of Holt and State of Nebraska, 5 have invented a new and useful Floor-Clamp, of which the following is a specification.

This invention relates to an improved floor clamp or jack, particularly designed for use by carpenters and others in laying floors, 10 weather - boarding, wainscoting, or other matched or unmatched lumber, and has for its object to provide a simple, inexpensive, and efficient device of this character by means of which the flooring-boards may be firmly 15 held together without scarring or otherwise mutilating the matched edges of the lumber.

The invention consists in the construction and novel combination and arrangement of parts, hereinafter fully described, illustrated 20 in the accompanying drawings, and pointed out in the claims hereto appended, it being understood that various changes in form, proportions, and minor details of construction may be resorted to without departing from 25 the principle or sacrificing any of the advantages of this invention.

In the accompanying drawings, forming a part of this specification, Figure 1 is a perspective view of a floor jack or clamp constructed in accordance with my invention. 30 Fig. 2 is a longitudinal sectional view showing in dotted lines the position of the operating-lever and clamping-lip when said lever is moved to operative position. Fig. 3 is a perspective view illustrating a modified form of 35 the invention.

Similar numerals of reference indicate corresponding parts in all the figures of the drawings.

40 The device forming the subject-matter of the present invention is particularly designed for laying superposed flooring or drop-siding over sheathing, and consists of a base-plate or body portion 5, preferably formed of a single 45 piece of metal or other suitable material, the side edges of which are bent downwardly to form depending flanges 6 and 7, provided at their opposite ends with spurs or teeth 8, adapted to engage the sheathing and prevent 50 slipping of the jack when in operation. Slidably mounted for longitudinal movement on the body portion 5 is a clamping-plate 9, provided with a longitudinally-disposed slot 10, through which passes a rivet or other suitable 55 fastening device 11, which serves to prevent accidental displacement of the parts

while at the same time permitting free sliding movement of said clamping-plate. One end of the plate 9 is bent downwardly to form a clamping-lip 12, while the opposite edges of 60 said plate extend beyond the flanges 6 and 7 and are provided with oppositely-disposed notches or recesses 13, adapted to receive the pivoted arms 14 of a pair of tongs 15. The free ends of the arms 14 are provided with 65 inwardly-extending lugs or spurs 16, which engage alined openings 17 in the depending flanges 6 and 7 and serve as a fulcrum for the tongs in operating the latter to clamp the 70 boarding in position.

In using the device for laying superposed flooring or laying weather-strips or drop-siding over sheathing the jack is placed in position slightly in advance of the board to be clamped and the terminal spurs 8 driven into 75 the sheathing to prevent slipping of the jack. The lugs 16 of the tongs are then introduced in the openings in the flanges 6 and 7, with the arms 14 engaging the recesses 13, and a forward pull exerted on the handles of the tongs, 80 thereby forcing the clamping-lip 12 into engagement with the edge of the board to be clamped, as will be readily understood.

If desired, a suitable clamping-block or strip may be inserted between the clamping-lip and the board, being forced in position as an additional protection against scarring or otherwise mutilating the notched edges of said 85 board.

In laying ordinary flooring the terminal 90 spurs of the body portion may be driven into the joist in front of the board to be clamped, or, if desired, the body portion and clamping-plate may be dispensed with, the inwardly-extending lugs of the tongs being driven into 95 the sides of the joist, as clearly shown in Fig. 3 of the drawings.

From the foregoing it is apparent that there is produced an extremely simple and inexpensive device admirably adapted for 100 the attainment of the ends in view.

Having thus described the invention, what is claimed is—

1. A floor-clamp comprising a base provided with depending flanges having openings formed therein, a clamping-plate slidably mounted on the base, and means engaging the openings in the flanges for forcing 105 said plate into engagement with the board to be clamped.

2. A floor-clamp comprising a base provided with oppositely - disposed depending

2
flanges having teeth or spurs formed thereon, a plate slidably mounted on the base and provided with a terminal depending clamping-lip, and means engaging said flanges and 5 sliding plate for forcing the terminal lip into engagement with the board to be clamped.

3. A floor-clamp comprising a base provided with oppositely - disposed depending flanges having alined openings formed there- 10 in, a clamping-plate slidably mounted on the base and having its opposite side edges provided with notches or recesses, and a pair of tongs the pivoted arms of which engage the openings in the flanges and the recesses in 15 the clamping-plate for forcing the latter into engagement with the board to be clamped.

4. A floor-clamp comprising a base formed of a single piece of metal the opposite edges

of which are bent to form depending flanges provided with terminal teeth or spurs, a plate 20 provided with an elongated slot slidably mounted on the base and having one end thereof bent downwardly to form a clamping-lip, a fastening means secured to the base and passing through the slot in the sliding plate, and means for reciprocating said plate to thereby force the terminal lip into engagement with the board to be clamped. 25

In testimony that I claim the foregoing as my own I have hereto affixed my signature 30 in the presence of two witnesses.

ESBON B. HATCH.
